UNITED STATES PATENT OFFICE.

HARRY TUNSTALL, OF FAIRHAVEN, MASSACHUSETTS, ASSIGNOR TO ALSATIAN MACHINE WORKS, LIMITED, OF BOSTON, MASSACHUSETTS, A CORPORATION OF MASSACHUSETTS.

SLIDING-BAR TOP-COMB FRAME.

Application filed November 14, 1923. Serial No. 674,711.

To all whom it may concern:

Be it known that I, HARRY TUNSTALL, a subject of George V King of England, and a resident of Fairhaven, in the county of Bristol and State of Massachusetts, have invented a new and useful Improvement in Sliding-Bar Top-Comb Frames, of which the following is a specification.

In United States Letters Patent No. 1,351,076, issued to me, and No. 1,416,951, issued to Joseph Fossel, there are described certain improvements on the well known Heilman comb. In Letters Patent No. 1,351,076 there are shown top combs each having a horizontal movement with means for moving it horizontally. I have found as the result of considerable study that the top comb mounting and the adjustable means for operating the top comb may be simplified in various details among others those which I shall now describe:—

My invention will be understood by reference to the drawings in which it is shown in its preferred form.

Figure 1 is a cross section of so much of a head of the type shown in my said patent as relates to my present invention, this view corresponding somewhat with Fig. 4 of my said patent and Fig. 1 of said Fossel patent.

Fig. 2 is a plan thereof.

Fig. 3 is a side elevation.

Figs. 4 and 5 are, respectively, a side elevation and a plan of the link mechanism connections, and

Figs. 6 and 7 are similar views of the top comb frame operating connections.

In these views certain of the reference characters of the said patents are used so that the location of my present improvement on the original machine may be easily seen. 13 is a shaft which is rocked by means such as are shown in my said patent or as shown in said Fossel patent, to cause the alternate movement of the nippers. In my said patent the top combs were operated by a different mechanism. Herein they are operated directly by the pendulum. The pendulum 12 in said Fossel patent is forked as at 12^a and is connected to the crank disk 9 by means substantially like that shown in the said Fossel patent so that the pendulum 12 and the shaft 13 may be given a lateral swinging movement which shall be equal in point of time and extent in each direction.

This arrangement comprises a carriage D having sleeves d running on rods C mounted in supports B on the frame A. Vertical ways D¹ mounted on said carriage carry a block D² with a hole through it in which lies a crank pin 10. In a housing 9^a or 60 crank disk 9 is mounted a block 10^a through which this crank pin 10 passes, and an adjusting screw 9^b passing through the outer wall of this housing adjusts the location of the block and crank pin toward and from the axis of the crank disk 9. The forked end 12^a of the pendulum 12 straddles a block e¹ which is pivotally mounted in the carriage D so as to turn slightly as required by the swinging movements of the pendulum. 70

On the shaft 13 is mounted the plate 14 fast thereto, while the pendulum 12 is loose on the shaft 13 and is adjustably held in place by screws 15 which pass through lugs in the plate 14 and engage the edges of the pendulum 12, which are shaped for the purpose as described in my said patent. Arms 32 carrying the nipper frames hang from studs 29 in position to be engaged by bowls 37 hung from shaft 13. 80

The plate 14 is provided with a slot 141 and a bolt 121 projects through the slot 141 and carries a nut by which the plate and pendulum are securely fastened together when the proper adjustment has been made by 85 the screws 15.

In describing the operations of the top comb it will be understood that the parts are duplicated on the two sides of the machine, and are operated in turn (as are the nipper frames) by the pendulum as it swings first in one direction and then in the other to turn the shaft 13. As the parts are identical, a description of the parts on one side only of a vertical line through the shaft 13 95 will be necessary.

In a companion application Serial No. 674,709 (Patent No. 1,535,701, Apr. 28, 1925), hereto I have shown means for operating the top comb by mounting it upon a frame which is operated by the arm 32^a similar to those shown in my said patent. In the present case I operate the top combs directly from the shaft 13 which is rocked by the pendulum 12. For this purpose I provide arms 36 mounted to turn with the shaft 13, to which arms are connected the ends of links 160, one on each side of the

machine, each link being operatively connected to a top comb frame as below described.

The top combs 48 are attached at each end to bell cranks 62 each of which is connected by a pin 161 to an arm 163 by a slot and bolt connection 164 of usual construction, so that the angle of the top comb may be adjusted. These arms comprise the top comb frame. These arms 163 are connected to be operated in the following manner: The outer end of each link 160 carries ways 165 in which is a block 166 mounted to be engaged by the forked end of a lever 167 attached 15 to the shaft 168. An adjusting screw 179 passes through one end of the casing forming the ways and is located to engage the block 166 to limit its throw. A spring 172 attached to the lower end of the lever 167 20 and to the frame A by a pin 173 holds the block 166 against the end of the screw 179.

Each arm 163 carrying the comb 48 is adjustably mounted on a slide 169 sliding in ways 170 formed in the casting A or attached thereto. Each slide 169 carries a block 169^a pivoted thereto and an arm 167^a mounted on shaft 168 to turn therewith and having a forked end, straddles the block 169^a so that as the shaft 168 is turned by the 30 link 160 and lever 167 it will rock the arm 167^a and cause the comb 48 to be given a horizontal movement. 171 is a screw which rests on the top of the slide piece 169 for the purpose of adjusting the position of the 35 top comb as well as maintaining it in proper position after its height is adjusted.

In case of any accident I provide a screw 174 at each side of the machine which passes through an arm mounted on the frame A 40 by the bracket 104 of my said patent which carries the shaft 103. The lower end of the lever 167 carries a stop piece 177 to engage the head of screw 174 in case of necessity.

It will be noted that by reason of the fact 45 that the adjacent ends of the links and the top comb frame are required to move horizontally, the top comb will also be required to move horizontally. Moreover, this construction lends itself to easy and simple adjustment. It will be understood that not only is this mechanism utilized in a double 50 machine in conjunction with the nippers on both sides of the machine as indicated in Fig. 1, but that when a number of heads 55 are used all operated, for example, from the same shaft 13, the mechanism may be repeated to cooperate with each head.

While this mechanism has been referred 60 to above as applied to the machine shown in U. S. Letters Patent No. 1,351,076 which is a double combing machine, it will be noted 65 that the mechanism on one side of this comb only has been described because the mechanism may be used equally well on a 70 single-sided machine provided proper os-

cillatory movements are given to means connected to the ends of the links 160.

What I claim as my invention is:—

1. In a combing machine, a top comb frame carrying a top comb and means for giving said top comb a horizontal movement comprising an oscillating shaft, a sliding member and ways whereby said sliding member may be moved horizontally and rectilinearly and a link connected at one end with said shaft and at the other end with said sliding member and connections between said sliding member and said top comb frame whereby the movements of said sliding member will be communicated to said top comb frame and said top comb will be given a similar horizontal rectilinear movement. 70

2. In a combing machine, means for operating a top comb comprising an oscillating shaft and a top comb frame, and connections comprising links and blocks operatively connected thereto, whereby the ends of said links farther from said shaft will be given a horizontal movement, and transmit 80 said horizontal movement to said frame. 85

3. In a combing machine, an oscillating shaft and a top comb frame and means connecting said shaft and said top comb frame comprising links connected at one end to said shaft and having at the other end ways, blocks running in said ways adapted to be moved therein by said links, a second shaft, levers mounted on said second shaft and operatively connected at one end to said blocks, 95 whereby the movement of said blocks will cause the rocking of said second shaft, 100 slideable mountings for one end of said top comb frame, and connections between said top comb frame mountings and said second shaft whereby said mountings and said top comb frame will be reciprocated. 105

4. In a combing machine of the kind described, a top comb frame, an oscillating shaft, a link connected thereto to be operated thereby, a sliding member and ways therefor, said sliding member being connected to said link whereby it will be given a horizontal reciprocation, a second shaft, connections between said sliding member and said second shaft whereby said second shaft will be operated and connections between said top comb frame and said second shaft comprising a second sliding member and rectilinear ways whereby said second sliding member may be moved horizontally and give to said top comb frame a horizontal movement. 110

5. In a combing machine, a top comb frame and means for intermittently reciprocating it horizontally comprising an oscillating shaft, a link connected thereto to be operated thereby, and connections between said link and said frame comprising means whereby the reciprocation of the frame may be adjusted with relation to the constant 115 120 125 130 135

movement of the link, said means comprising ways located in the outer end of said links, a block running in said ways and adapted to be moved thereby, and a set screw in said ways adapted to engage and cause the movements of said blocks.

6. In a combing machine, a top comb frame and means for intermittently reciprocating it horizontally comprising an oscillating shaft, a link connected thereto to be operated thereby, and connections between said link and said frame comprising means whereby the reciprocation of the frame may be adjusted with relation to the constant movement of the link, said means comprising ways located in the outer end of said links, a block running in said ways and adapted to be moved thereby, and a set screw in said ways adapted to engage and cause the movements of said blocks, and slides adjustably connected to said frame, a rock shaft carrying a lever connected to said block whereby the movement of said block will rock said shaft, and arms connected to said rock shaft and frame slides whereby said rock shaft will move said frame.

7. In a combing machine, a top comb frame and means for intermittently reciprocating it horizontally comprising an oscillating shaft, a link connected thereto to be

operated thereby, and connections between said link and said frame comprising means whereby the reciprocation of the frame may be adjusted with relation to the constant movement of the link, said means comprising ways located in the outer end of said links, a block running in said ways and adapted to be moved thereby, and a set screw in said ways adapted to engage and cause the movements of said blocks, and slides adjustably connected to said frame, a rock shaft carrying a lever connected to said block whereby the movement of said block will rock said shaft, and arms connected to said rock shaft and frame slides whereby said rock shaft will move said frame.

8. In a combing machine, a top comb frame, means for reciprocating it pivotally connected thereto, and means for supporting its free end comprising horizontal members and adjusting screws passing through said frame and adapted to rest on said horizontal members.

HARRY TUNSTALL.
